CLAIM

The ornamental design for a legrest attachment for a
chair, as shown and described.

DESCRIPTION

FIG. 1 is a perspective view of a legrest attachment for
a chair showing my design;

FIG. 2 is a side elevational view of the footrest attach-
ment of FIG. 1;

FIG. 3 is a rear elevational view of the footrest attach-
ment of FIG. 1;

FIG. 4 is a top plan view of the footrest attachment;
and

FIG. 5 is a perspective view thereof, a chair being
shown in broken lines therein for illustrative purposes
only.

FIG. 2

FIG. 3

FIG. 4

FIG. 5
